UNITED STATES PATENT OFFICE.

JOHN C. ADKINS, OF STOCKTON, CALIFORNIA.

APPARATUS FOR BORING WELLS.

SPECIFICATION forming part of Letters Patent No. 769,371, dated September 6, 1904.

Application filed April 11, 1904. Serial No. 202,485. (No model.)

To all whom it may concern:

Be it known that I, JOHN C. ADKINS, a citizen of the United States, residing at Stockton, in the county of San Joaquin, State of California, have invented certain new and useful Improvements in Apparatus for Boring Wells; and I do declare the following to be a full, clear, and exact description of the invention, such as will enable others skilled in the art to which it appertains to make and use the same, reference being had to the accompanying drawings, and to the numerals of reference marked thereon, which form a part of this specification.

15 My invention relates to improvements in apparatus for boring wells, and particularly to that class designated as "reamers;" and it consists in the effective construction herein-after set forth.

20 My object is to produce a reamer which will sufficiently ream and clear the hole, so that the casing may be easily inserted without a waste of energy or without reduction in size. This object I accomplish by the peculiar construction and adaptation of parts fully set forth in this specification and particularly pointed out in the claims appended.

In order that my invention may be readily understood and easily carried into effect, I 30 will proceed, aided by the accompanying drawings, fully to describe the same.

Referring to the drawings, Figure 1 is a longitudinal sectional view of my improved reamer. Fig. 2 is a bottom plan view of the 35 same.

Similar numerals of reference indicate corresponding parts in both views.

1 designates the casing of my improved reamer.

40 1^a is an ordinary bail riveted to the casing 1.

1^b is a cable attached to same.

2 designates slots of suitable length and width cut near the bottom of the casing 1 at points equidistant from each other.

45 3 designates steel springs riveted to the casing 1 in the top thereof. Said springs bend inwardly into inverted-L shapes at the bottom of the casing. There is one spring 3 to each slot 2, and said springs fit over said slots.

50 4 designates steel blocks fitted into the slots

2 and riveted to the springs 3. Said blocks extend a suitable distance within the casing 1.

5 designates steel springs riveted to the blocks 4 within and extending upward in the casing 1. Said springs are at the place where 55 they are fastened to the blocks 4 a trifle wider than the slots 2.

6 is a steel key located between the springs 5.

7 is an iron pin fastened into the head of the key 6.

8 is a piece of cast-iron exactly fitted into the casing 4 and surrounding the pin 7 and resting on the key 6.

9 is a cap screwed onto the top of the pin 7, adapted to hold the part 8 in position.

65 10 is an eye-screw tapped into the top of the part 8. 11 is a cable attached thereto.

12 designates chisels riveted to the inverted L of the steel springs 3 by means of rivets 13. Said chisels follow the circumference of the 70 casing 1.

The operation is as follows: The cable 11 is held taut while the reamer follows the casing of the well down until it strikes the bottom. Then the cable 11 is loosened and the jar of 75 the reamer striking the bottom causes the iron 8 to slip downward with great force. This drives the key 6 downward, which in turn throws the parts 3, 4, and 5 outward, and the chisels 12 then ream the hole to a greater 80 width than the width of the casing of the well, and thus permits said casing to slip easily downward without reduction. When the reamer comes to a stop, the part 8 is pulled upward by means of the cable 11 and pulls 85 the key 6 back into its position. The whole reamer is then pulled upward by means of the cable 1^b. The springs 3 spring the parts 4 and 5 back in position, and the key 6, fitting between the springs 5, holds said parts in position, and the reamer is ready for another drive.

Although I have shown a certain kind of mechanism for spreading the spring-chisel mechanism, still any which is adaptable may 95 be used.

I have shown four of the slots 2 and the corresponding parts. Any number desired, however, may be used.

I have entered into a detailed description of 100

the construction and relative arrangement of parts embraced in the present and preferred embodiment of my invention. I do not desire, however, to be understood as confining myself to such specific detail, as such changes and modifications may be made in practice as fairly fall within the scope of my claims.

Having thus described my invention, what I claim as new and useful, and desire to protect by Letters Patent, is—

1. In an apparatus of the kind described the combination of a suitable casing provided with a plurality of vertical slots near the bottom thereof, steel springs riveted to the outside top of said casing and extending downwardly over said slots, said springs being bent inwardly into inverted-L shapes at the bottom of said casing, steel blocks riveted to said springs and extending a suitable distance through said slots, steel springs riveted to said blocks inside the said casing and extending a suitable distance upward therein, a suitable driving-key mechanism fitted between and above said last-named springs, and suitable chisels fastened to the inverted-L shapes on the first-named springs, all for the purpose set forth.

2. In an apparatus of the kind described the combination of a cylindrical casing having a plurality of vertical slots near the bottom thereof, a spring-chisel mechanism fastened to said casing and acting in said slots, chisels carried by said mechanism and suitable means within said casing for operating said chisel mechanism, all as set forth.

3. In an apparatus of the kind described the combination of a suitable cylindrical shell, a spring-chisel mechanism fastened to said shell, downwardly-extending chisels carried by said mechanism, and means for flaring and retracting said mechanism, all for the purpose set forth.

4. In an apparatus of the kind described the combination of a suitable shell, a suitable key within said shell, a suitable pin screwed into the head of said key, a piece of cast-iron surrounding said pin and resting on said key, a cap screwed onto the top of said pin and adapted to hold said piece of cast-iron in position, an eye-screw tapped into the top of said piece of cast-iron, a cable attached thereto, and a

suitable spring-chisel apparatus attached to said casing and regulated by said key, all as set forth.

5. In an apparatus of the kind described the combination of a suitable casing provided with a plurality of vertical slots near the bottom thereof, steel springs riveted to the outside top of said casing and extending downwardly over said slots, said springs being bent inwardly into inverted-L shapes at the bottom of said casing, suitable chisels fastened to the inverted-L shapes on the springs, steel blocks fastened to said springs and extending a suitable distance through said slots, steel springs fastened to said blocks inside of the said casing and extending a suitable distance upward therein, a suitable driving-key fitted between said last-named springs, a pin fastened into the top of said key, a piece of cast-iron surrounding said pin, a cap on the top of said pin adapted to hold said cast-iron in position, and means for raising said casing and said key, pin, and iron, all as set forth.

6. A reamer consisting essentially of a casing 1 having a plurality of vertical slots 2 near the bottom thereof, the springs 3 fastened to the top of said casing and extending downwardly over the slots 2, said springs being bent inwardly into inverted-L shapes at the bottom of said casing, the chisels 12 fastened to the said inverted-L shapes, the blocks 4 fastened to the springs 3 and extending any desired distance through the slots 2, the springs 5 fastened to the blocks 4 on the inside of the casing 1 and extending upwardly any desired distance, the key 6 located between said last-named springs, the pin 7 fastened into the head of said key, the iron 8 surrounding the pin 7, the cap 9 on the pin 7 adapted to hold the part 8 in position, the eye-screw 10 tapped into the top of the part 8, the cable 11 attached thereto, the bail 1^a fastened to the top of the casing 1, and the cable 1^b attached thereto, all as set forth.

In testimony whereof I have signed my name to this specification in the presence of two subscribing witnesses.

JOHN C. ADKINS.
